Primary Examiner — Ruth McInroy(74) *Attorney, Agent, or Firm* — Ryan Kromholz & Manion, S.C.**CLAIM**

The ornamental design for a face mask, as shown and described.

DESCRIPTION

FIG. 1 is an exploded front elevation view of a face mask showing my new design, the rear view being identical; FIG. 2 is an exploded front perspective view thereof showing the article in use;

FIG. 3 is a front perspective view thereof;

FIG. 4 is a right side elevation view thereof;

FIG. 5 is a left side elevation view thereof;

FIG. 6 is a front elevation view thereof;

FIG. 7 is a rear elevation view thereof; and,

FIG. 8 is a top plan view thereof.

The broken lines are for illustrative purposes only and form no part of the claimed design.
